UNITED STATES PATENT OFFICE.

GEORGE M. CHARLES, OF WASHINGTON, DISTRICT OF COLUMBIA.

FOUNTAIN COMB.

1,413,320.

Specification of Letters Patent. Patented Apr. 18, 1922.

Application filed August 24, 1921. Serial No. 495,148.

To all whom it may concern:

Be it known that I, GEORGE M. CHARLES, a citizen of the United States, residing at Washington, in the District of Columbia, 5 have invented certain new and useful Improvements in Fountain Combs; and I do hereby declare the following to be a full, clear, and exact description of the invention, such as will enable others skilled in the art 10 to which it appertains to make and use the same.

This invention relates to combs and more particularly stated contemplates the production of a fountain comb which can be 15 easily held in the hand and through which material of either a liquid or gaseous nature can be directed for washing or otherwise treating the hair.

It is an object of my present invention to 20 form a comb with a material receiving compartment which latter is provided with a series of unrestricted discharge openings located adjacent the respective teeth of the comb and adapted to deliver a stream of material along the under face of the teeth toward the point or extreme end thereof.

Another object of my invention is to provide a fountain comb the several teeth of 30 which are arcuately disposed and the general contour of the comb being of such curved shape as to be readily held in the hand and otherwise conform to the palm and fingers of the hand when in a natural washing or shampooing position. A further object of 35 my invention is to provide a comparatively inexpensive and relatively light fountain comb free from valves and other associated liquid controlling devices which have heretofore been used.

40 In the accompanying drawings, and wherein similar reference characters designate corresponding parts in the several views:—

Fig. 1 is a perspective view of my im- 45 proved comb showing a connection therefor in dotted lines;

Fig. 2 is a side elevation of the comb illustrating the curved contour of the comb which readily conforms to the hand;

50 Fig. 3 is a longitudinal sectional view through the comb; and

Fig. 4 is a view looking against the under 55 face of the comb and illustrating the discharge openings in their close relation to the several teeth of the comb.

My present invention has been designed as

an improvement over several patents already granted to me.

Heretofore valved devices have been associated with the material receiving chamber, and the user has controlled at will the discharge of the liquid from the comb. Certain disadvantages have been experienced in the use of these known forms of fountain combs. In practice it has been found that 65 the supply of the material can be best controlled from a valve at or approximating the source of supply, leaving the hand and fingers free to properly grasp and manipulate the comb.

70 It therefore has been found possible to design a simple, light and particularly effective comb having a shape not unlike that of the human hand and fingers, and a cleansing action similar to the passage of the fingers 75 through the hair. In shape my comb is relatively shallow or thin, and can be easily and comfortably positioned in the hand and effectively moved through the hair in a natural manner as will be understood.

80 Referring to the drawings the comb is formed of a unitary or one piece casting of any suitable material, and comprises a casing or body portion 1 from which project the teeth 2. The upper wall of the casing 1 85 is curved and merges into the upper faces of the teeth, which latter are also perceptibly curved as shown. Both of said curved portions form a continuous convex surface for fitting the palm of the hand when slightly 90 curved. The bottom wall of the casing is substantially flat and merges into the under faces of the teeth at an angle as shown. The teeth and the spaces formed therebetween constitute what might be termed the front 95 wall of the comb. The rear wall 3 of the casing unites the respective top and bottom walls, and as shown is preferably flared at its center to form a boss 4 into which latter a nipple or hose connection 5 is threaded.

100 Formed within the casing 1 which is closed at both ends by relatively fixed or stationary end walls is the material receiving chamber 6, (see Fig. 3). In cross section it is of triangular formation, and in 105 capacity it is sufficiently large to insure a steady discharge of the material through the openings 7. An opening is preferably provided for each tooth of the comb. The openings are slantingly arranged within the 110 bottom wall of the casing and serve to direct the material against substantially the entire

under face 8 of each tooth. From a stand-point of communication as viewed in Fig. 3, the opening 7 serves to substantially align the flow of the liquid as it enters the intake nozzle with the under face of the centrally positioned teeth against which it is discharged. When in use, the material flows from the chamber of the comb through the openings 7 along the under face of the teeth 10 to the extreme ends thereof, and is immediately available against the surface over which the comb is moved. By this construction the material is prevented from spraying above the comb, and the force of 15 each stream is concentrated at the point or end of each tooth. The end teeth are shown as not provided with openings 7, thereby reducing the tendency of the material to unduly spread or trickle beyond the comb 20 and the surface over which the comb is being moved.

A hose or similar connection shown in dotted lines in Fig. 1, is fitted upon the nipple or connection 5, and the passage of the 25 material into the chamber of the comb can be readily regulated from the source of supply.

It will be understood that the comb can be made of varying size and capacity, and 30 of a material which will be both durable, and light in weight. The shape of the comb may also be slightly varied. It is apparent however, that the contour of the comb conforms to the human hand and in use produces results which are similar to the hand 35 and more especially the finger rubbing commonly practiced in washing the hair.

I claim:

1. A fountain comb comprising a casing 40 provided with relatively stationary end walls and having a chamber therein, a series of teeth projecting from the casing and forming integral continuations thereof, and means including a series of relatively small 45 openings provided in the chamber for delivering the material against the under face of the teeth of the comb.

2. A fountain comb comprising a one piece casing closed at both ends and having a 50 curved upper wall and a series of projecting

curved teeth forming continuations of the curve of the aforesaid upper wall, a chamber in said casing, an inlet for said chamber and an outlet arranged adjacent the teeth of the comb for discharging the material against substantially the entire under face of the teeth of the comb and toward the extreme ends thereof.

3. A fountain comb comprising a one piece casing provided with relatively stationary 60 end walls and formed with a curved wall and projecting teeth forming a continuous convex surface for fitting the hand when slightly curved, a chamber in said casing, an inlet for the chamber, and an outlet for 65 delivering material to the ends of the aforesaid teeth.

4. A fountain comb comprising a one piece casing closed at both ends and formed with a curved wall and projecting curved teeth 70 forming a continuous convex surface arranged and adapted to conform to the curvature of the hand when held therein, a material receiving chamber in said comb, an inlet for said chamber, and an outlet for discharging 75 the material from the chamber against substantially one entire face of the teeth of the comb and toward the extreme ends thereof.

5. A fountain comb comprising a casing 80 provided with relatively stationary end walls, said casing being formed with a curved wall and projecting curved teeth arranged and adapted to conform to the curvature of the hand when held therein, a material receiving chamber in said comb, an inlet for said chamber upon one side of the casing, and a series of outlet openings arranged at the juncture of the teeth of the comb with the casing, each of said openings being 85 adapted to deliver a stream of material against substantially the entire under face of the teeth of the comb and toward the extreme ends thereof.

In testimony whereof I affix my signature, 95 in presence of a subscribing witness.

GEORGE M. CHARLES.
